UNITED STATES PATENT OFFICE.

FREDERICK L. CUMMINGS, OF MALDEN, MASSACHUSETTS.

DEVICE FOR FEEDING FLEXIBLE MATERIAL.

933,890.

Specification of Letters Patent. Patented Sept. 14, 1909.

Application filed November 23, 1907. Serial No. 403,481.

To all whom it may concern:

Be it known that I, FREDERICK L. CUMMINGS, a citizen of the United States, residing at Malden, in the county of Suffolk and State of Massachusetts, have invented new and useful Improvements in Devices for Feeding Flexible Material, of which the following is a specification.

This invention relates to a device for feeding wire, sheet material, or the like, the same being particularly adapted to feed wire, sheet material, or the like intermittently at a high speed and in considerable lengths from a reel of the same.

It is well known to those skilled in the art that when it is desired to feed lengths of wire accurately and at high speed from a reel of the same that the feeding device is very liable to be inaccurate on account of the wire slipping during the feeding movement. This is especially true where the feeding movement is an intermittent one and where the wire is fed from a reel, for the reason that the reel has to be rotated by the feed mechanism and this necessitates considerable power so that the wire is liable to slip between the feeding instrumentalities and cause pieces intermittently fed thereby to be of different lengths.

It is the object of this invention to overcome such inaccuracies and to this end two separate feeding mechanisms are employed in one device for feeding the wire. One of these mechanisms feeds the wire in accurate lengths, or spaces the same off in readiness to be cut in lengths, the other feeding mechanism is a supply mechanism which draws the wire from the reel and through the straightener and keeps a supply of slack wire between the two mechanisms, so that all the spacing feed mechanism has to do is to draw the requisite length of wire at each feeding movement from said supply of slack wire between the two feeding mechanisms.

This supply of slack wire is preferably fed by the first feeding mechanism in the form of a loop from which loop the second feeding mechanism draws its supply for the accurate lengths of wire which are intermittently fed thereby.

I have described my device in the following specification and illustrated the same in the drawings, Figures 1 to 6, as particularly adapted to feed wire, and in Figs. 7

to 14, inclusive, I have illustrated another form of my invention the same being particularly adapted to feeding sheet material such as strips or sheets of paper and the like.

The invention consists primarily in a device for feeding wire, sheet material, or the like which employs two independent feeding mechanisms, one of said mechanisms adapted to draw the wire, sheet material, or the like from its source of supply, such, for instance, as a reel and in case wire is being fed to draw said wire through the wire straightener. The other of said mechanisms is adapted to feed the wire, sheet material, or the like in lengths and preferably to feed the same intermittently from a supply of slack wire, sheet material, or the like located between the two feeding mechanisms, said supply of slack wire, sheet material, or the like being supplied by the first feeding mechanism and preferably formed in the shape of a loop.

The invention further consists in the combination and arrangement of parts set forth in the following specification and particularly pointed out in the claims thereof.

Referring to the drawings: Fig. 1 is a plan view of my improved device for feeding wire, sheet material and the like. Fig. 2 is a front elevation of the same, broken away. Fig. 3 is a detail sectional elevation taken on line 3—3, Fig. 1, illustrating the mechanism by which the wire is fed continuously. Fig. 4 is a detail sectional elevation taken on line 4—4, Fig. 1. Fig. 5 is a detail sectional elevation taken on line 5—5, Fig. 4. Fig. 6 is a sectional elevation taken on line 6—6, Fig. 2. Fig. 7 is a plan view of another form of my invention the same being particularly adapted for feeding sheet material such as paper or the like. Fig. 8 is a right hand side elevation of the mechanism illustrated in Fig. 7. Fig. 9 is an end elevation of the same as viewed from the lower side of Fig. 7. Fig. 10 is a sectional elevation taken on line 10—10, Fig. 8, illustrating the intermittent feeding mechanism. Fig. 11 is a sectional elevation taken on line 11—11, Fig. 10, looking toward the left in said figure. Fig. 12 is a longitudinal sectional elevation taken on line 12—12, Fig. 11, looking in the direction of the arrows on said line. Fig. 13 is a detail sectional ele-

vation taken on line 13—13, Fig. 9. Fig. 14 is a detail sectional elevation taken on line 14—14, Fig. 7.

Like numerals refer to like parts throughout the several views of the drawings.

In the drawings, Figs. 1 to 6, inclusive, 10 is a frame of suitable construction, and 11 is the main driving shaft journaled in suitable bearings upon the frame 10 and driven by means of a pulley 12. The wire is fed from a reel through a wire straightener 13 of well known construction, said wire straightener being supported upon the frame 10. The mechanism for imparting a continuous feed to the wire in order to secure the slack wire between the two feeding mechanisms is particularly illustrated in Figs. 1, 2 and 3. The wire is fed by means of two feed rolls 14 and 15 having oppositely inclined peripheries. The lower feed roll 14 is fast to a shaft 16 which has a bearing at its outer end in the frame 10 and at the other end thereof in a bearing 17 on the frame 10. A bevel gear 18 fast to the shaft 16 meshes into another bevel gear 19 fast to the shaft 11 by which it is driven. The upper conical feed roll 15 rotates upon a stud 20 fast to an arm 21 which is pivoted to a stud 22. A screw-threaded rod 23 pivoted at 24 to the frame projects upwardly through the arm 21 and engages a hand nut 25 by means of which the arm 21 and the feed roll 15 rotatably supported thereon are forced downwardly to bring more or less pressure to bear upon the wire 27 which is fed between the two rolls 14 and 15. A spring 26 encircles the rod 23 between the nut 25 and the arm 21. The wire 27 is guided between the feed rolls 14 and 15 by a wire guide 28, said wire passing through a slot 29 provided in said wire guide. The wire guide 28 is rigidly fastened to the frame of the machine by a screw 30 and when it is desired to increase or diminish the amount of wire fed in a certain time by the feed rolls 14 and 15, said screw 30 is loosened and the wire guide 28 moved laterally so as to move the wire 27 longitudinally of and between said feed rolls 14 and 15. It will be seen that if, referring to Fig. 3, the wire guide is moved toward the left, a greater amount of wire will be fed during a certain time and if moved toward the right, a less amount of wire will be fed during a certain time, it being understood that the lower roll 14 is the positively driven feed roll and that the upper roll 15 is an idler. The wire 27 is fed forwardly by the continuous feed mechanism hereinbefore described to form a loop of slack wire 31 and this loop is supported upon a suitable frame consisting of an arm 32 which has fastened to its lower end a clamp sleeve 33, Figs. 1, 2 and 6. The clamp sleeve 33 is fastened to the arm 32 by bolts 34 and encircles a hub 35 formed upon a bracket 36

fast to the frame 10. The clamp sleeve 33 is tightened upon the hub 35 by means of a bolt 37; thus it will be seen that the arm 32 may be set at different angles to the horizontal frame, as may be desired, for the purpose hereinafter set forth. The arm 32 forming a portion of the wire supporting frame has transverse arms 38, 38 rigidly fastened thereto with a space 39 therebetween through which the loop 31 projects. Side arms 40, 40 connect the transverse arms 38, 38 and are designed to still further guide and support the loop 31 of wire.

Wire is fed intermittently in accurate lengths by means of the intermittent feed mechanism at the right of Fig. 1 and particularly illustrated in Figs. 2, 4 and 5. This intermittent wire feeding mechanism consists of two feed rolls 41 and 42, the upper feed roll 42 consisting of a segmental plate which is fastened to a gear 43 which in turn is fastened to a shaft 44 journaled in suitable bearings upon the frame of the machine and having fastened to its inner end a bevel pinion 45 which meshes into a bevel gear 46 fast to the driving shaft 11. The lower feed roll 41 is fastened to a gear 47 which rotates upon a stud 48 projecting from the end of a lever 49 pivoted upon a stud 50 and having a cam roll 51 rotatably supported upon its inner end and bearing against the periphery of a cam 52. A spring 53 holds the cam roll 51 in engagement with the cam 52.

The stud 50 upon which the lever 49 is pivoted is an eccentric stud and is rigidly fastened to the frame 10 by means of a nut 54 having screw-threaded engagement therewith. By loosening the nut 54 and rotating the stud 50 in one direction or the other, the lever 49 may be moved upwardly or downwardly, as desired, thus moving the lower feed roll toward or away from the upper segmental feed plate 42. The purpose of this adjustment is to adjust the space between the rolls in order to adjust the grip of said rolls upon the wire and to accommodate different gages of wire. When the lever 49 is rocked by the cam 52 the lower feed roll 41 will coact with the segmental feed roll 42 to feed a certain length of wire. The length of wire fed depends upon the length of time when the feed roll 41 is pressing the wire against the segment 42 and this length of time can be varied in two ways, one by changing the segment 42 for segments of different lengths, the other method would be to change the position of the cam 52 upon the shaft 11. Said cam 52 it will be noted is fastened to the shaft 11 by means of a set screw 55 so that the cam can be adjusted circumferentially thereof upon the shaft 11 and thus change the time when the feed roll 41 will be moved upwardly to coact with the segment 42 and hence the length of wire fed

by said rolls may be increased or diminished by changing the position of the cam upon the shaft or by substituting different length segments, as hereinbefore set forth.

5 The wire is guided from the loop 31 by means of a guide 56 between rolls 57 and 58 which act to retard the wire in its feeding movement, or in other words, act as a brake. The upper roll 57 is journaled upon an arm 59 pivoted to a stud 60 and is held in contact with the wire which passes between said rolls by a spring 61. A friction is applied to the roll 57 to retard the same in its rotation by means of a spring 62 which encircles the stud upon which said roll rotates and is pressed toward said roll by means of nuts 63, 63 having screw-threaded engagement with said stud. An auxiliary guide 64 is fastened to the arm 59 to direct the wire in the proper direction between the rolls 57 and 58. After the wire passes out from between the feed rolls 41 and 42 it is preferably guided by a suitable tubular guide 65 toward the machine which is to sever pieces 20 therefrom to be utilized, as may be desired.

25 When the wire passes out of the guide 65 it is liable to have a permanent set imparted thereto which has not been entirely removed when passing through the straightener before entering the feeding device hereinbefore described, and this set oftentimes guides the wire in the wrong direction to feed the same properly to the machine which is to utilize the wire preferably by cutting the same into 30 pieces to be bent into desired shapes. The novel construction of the wire supporting frame which consists of the arm 32, cross arms 38, 38, side arms 40, 40, and clamp sleeve 33 is designed to overcome this set of 35 the wire and guide said wire in the desired direction independent of said set. This object is attained by tipping said wire supporting frame at different angles according to the set of the wire and this tipping of the frame at different angles tips the loop 31 supported thereon at corresponding angles and thus turns the free end of the wire 27 as it issues from the tubular guide 65 so that the same will point in the desired direction 40 or toward the point to which it is desired to feed the wire in the machine which is to utilize the same.

45 It will be readily seen that the manner in which the wire supporting frame is adjusted for this purpose is to loosen the clamp bolt 37 thus loosening the grip of the clamp sleeve 33 upon the stationary hub 35, then tipping the frame upwardly or downwardly, as may be desired, in order to turn the free 50 end of the wire so that it shall feed in the desired direction. When the free end of said wire is thus adjusted the wire supporting frame is set rigidly in position by tightening the clamp bolt 37.

55 The general operation of the mechanism

hereinbefore specifically described is as follows: The wire is fed continuously from the reel through the straightening device by means of the rolls 14 and 15 to form a large loop 31 of slack wire which rests upon the 70 supporting frame composed of the arms 32, cross arms 38, 38 and side arms 40, 40. Said wire is fed intermittently in lengths, as may be desired, by means of the feed rolls 41 and segmental feed roll 42. Said intermittent feed rolls are rotated as hereinbefore described. In the particular form of my invention illustrated in the drawings, it will be seen that the bevel gear 46 is in the proportion of about three to one relatively to 80 the gear 45 so that for one rotation of the shaft 11 the shaft 44 and the segmental feed roll 42 will be rotated three times, but the feed roll 41 will only be brought toward the segmental feed roll 42 to feed the wire, once 85 for each rotation of the shaft 11 by means of the lever 49 and the cam 52, the object of this increased gearing being to feed in a short time a long piece of wire. If it is found that the loop 31 is gaining in length 90 and storing up too much slack wire, the operator loosens the nut 25 and thus decreases the pressure upon the arm 21 through the spring 26 until the rolls 14 and 15 cease to feed the wire. He leaves the rolls in this 95 condition until the surplus amount of wire in the loop has been taken up by the intermittent mechanism, when he again tightens the nut 25 and the rolls 14 and 15 again feed the wire continuously to the loop.

100 If it is desired to increase or diminish the amount of wire which is fed by the intermittent mechanism it may be done in either of the ways hereinbefore referred to, namely, by adjusting the cam 52 upon its shaft or 105 by changing the segmental plate 42 for a longer or shorter one.

If it is desired to adjust the roll 41 toward or away from the segmental feed roll 42 for different gages of wire or if for any 110 reason it is desired to increase or diminish the space between said rolls it may be done by means of the eccentric stud 50, as hereinbefore set forth. The mechanism by which the different feed rolls are rotated has been 115 hereinbefore fully described.

120 It is not essential to my feeding mechanism that the feed roll 41 should be journaled upon the end of a lever such as 49 and operated by means of a cam. In some cases this specific mechanism may be omitted and the feed rolls 41 and 42 geared together as shown, but the feed roll 41 may be rotatably supported upon a stationary stud instead of upon the lever 49 without departing from 125 the spirit of my invention, this being the particular mechanism shown and described for rotating the rolls 41 and 42 and for moving the roll 41 toward and away from the segmental roll 42 for the purpose as stated 130

of intermittently feeding a large amount of wire in a short space of time.

In Figs. 7 to 14, inclusive, another form of my invention is illustrated, in which the mechanism is particularly adapted to feed sheet material such as sheets of paper and the like; and referring to these figures, 67 is a base, the continuous feed mechanism 68 being supported on said base at the left hand end thereof, Fig. 8, and the intermittent feed mechanism 69 being supported upon said base at the right of said figure. A strip of sheet material, paper or the like 70 is illustrated as being fed through the machine by the continuous feed mechanism 68 and the intermittent feed mechanism 69. The continuous feed mechanism consists of an upper roll 71 and a lower roll 72. The lower roll 72 is fast to a shaft 73 journaled in suitable bearings in brackets 74 and 75 fast to the base 67. To the inner end of the shaft 73 is fastened a disk 76 and this disk is rotated by a driving disk 77, the periphery of which is arranged to bear against one face of the disk 76.

The driving disk 77 is mounted upon a driving shaft 78 and is splined thereto and movable longitudinally thereof. Said driving disk has a hub which is provided with an annular groove 79 which is engaged by a pin 80 fast to a lever 81 pivoted at 82 to a stand 83 fast to the base 67. The shaft 78 is journaled to rotate in suitable bearings 84 and 85 fast to the base 67 and is driven by a pulley or other suitable means (not shown). An idler roll 86 is rotatably supported upon a stud 87 which is fast to a bracket 88 fast to the base 67 of the machine and the periphery of this idler roll 86 bears against the opposite face of the disk 76 to that which contacts with the periphery of the driving disk 77. By moving the lever 81 which is locked in position by suitable means not shown in the drawings, the driving disk 77 may be moved toward or away from the center of the shaft 73 to which the disk 76 is fastened, so that the speed of rotation of said disk 76, its shaft 73, and the lower continuous feed roll 72 may be varied, as desired. The upper continuous feed roll 71 is rotatably mounted upon a shaft 89 fast to a rocker frame 90 pivoted at 91 to a supporting frame 92. The supporting frame 92 is pivoted at 93 to the bracket 75 and is forked at its outer end to receive a stud 94 fast to the bracket 74. The stud 94 is screw-threaded to receive a nut 95 which bears against the under side of the forked end of the supporting frame 92 so that by rotating the nut 95, said supporting frame, the rocker frame 90, and the roll 71 may be moved away from the roll 72 or may be allowed to descend until the roll 71 is in contact with the roll 72 or with the paper 70 which is being fed therebetween.

The intermittent feed mechanism 69 consists of two feed rolls 96 and 97, the lower feed roll 97 being fastened to a shaft 98 journaled to rotate in suitable bearings provided in the brackets 99 and 100 fast to the base 67. The shaft 98 together with the feed roll 97 is rotated by means of a gear 101 fast thereto and meshing into a gear 102 fast to a shaft 103 also journaled to rotate in bearings provided in the brackets 99 and 100. The shaft 103 has a bevel gear 104 meshing into a bevel gear 105 which is fastened to the driving shaft 78. The lower roll 97 has fastened to its periphery and forming a portion thereof end sleeves 106, 107, each of said end sleeves having a segmental flange 108 thereon and between the sleeves 106 and 107 is a central sleeve 109 which is provided on its opposite ends with segmental flanges 110, 110. The sleeves 106 and 107 are permanently fastened to the roll 97 and the sleeve 109 is adjustably fastened thereto by means of a screw 111 having screw-threaded engagement with said roll 97 and extending through a block 112 which is beveled at its opposite sides to engage the corresponding bevel sides of a slot 113 extending partly around the sleeve 109.

By loosening the screw 111 the sleeve 109 may be rotated upon the roll 97 to such a position as to bring the flanges 110, 110 in alignment with the flanges 108, 108 laterally thereof or it may be rotated until the flanges 110, 110 extend beyond the flanges 108, 108 and thus increase as a whole the length of the segmental flange upon the feed roll 97, said segmental flange being composed as a whole of the flanges 108, 108 and the continuations thereof formed by the flanges 110, 110. The upper feed roll 96 is fast to a shaft 114 journaled to rotate upon arms 115 and 116 forming a portion of a rocker frame 117. The arms 115 and 116 are pivoted upon bearing screws 118 having screw-threaded engagement with the brackets 99 and 100. The arm 116 extends longitudinally of the strip of material 70 toward the left, Fig. 8, beyond the arm 115 and has a roll 119 journaled thereon and adapted to bear against the periphery of a cam 120 which is fastened to the shaft 103. A stop screw 121 has screw-threaded engagement with the bracket 100 and limits the extent of downward movement of the rocker frame 117 by abutting against the underside of the arm 116, thus regulating the distance to which the upper roll may descend.

The general operation of the device hereinbefore specifically described and illustrated in Figs. 7 to 14, inclusive, is as follows: The paper or other sheet material 70 is fed between the feed rolls 71 and 72 which rotate continuously and at such a speed as to form a loop of said paper between the continuous feed mechanism 68 and the inter-

mittent feed mechanism 69. The paper which is fed by the intermittent feed mechanism is drawn from this loop by the feed rolls 96 and 97. The feed roll 96 is lowered 5 into contact with the segmental flanges 108 and 110 upon the feed roll 97 by the cam 120 which is so timed as to allow the roll 119 to descend together with the rocker frame 117 just as the end of the segment comes 10 beneath the center of the roll 96, as illustrated in Fig. 11. The paper is then caught between the upper feed roll 96 and the lower feed roll 97 or the segments thereon and is fed a distance depending upon the length of 15 said segments. This distance may be equal to the length of the segments 108 or 110, or it may be equal to the length of a segment 108 plus the length of a segment 110, or it may be fed any distance between said lengths 20 according to the position of the sleeve 109 upon the roll 97.

If it is found that the loop between the two feeding mechanisms is becoming too short, the driving disk 77 is moved toward the 25 center of the rotary disk 76, thus increasing the number of rotations of said disk and the shaft 73 to which it is fastened. If it is found that the loop of paper between the two feeding mechanisms is becoming too 30 long, then the driving disk 77 is moved away from the center of the disk 76 to decrease the number of rotations thereof and consequently of the shaft 73 and the feed roll 72 fast thereto. If it is desired to stop the continuous feed for any reason while the intermittent feed is continuing to operate, the operator may move the upper feed roll 71 away from the lower feed roll 72 by screwing the nut 95 upwardly on the stud 94. If 35 it is desired to stop the intermittent feed the screw 121 may be screwed upwardly and thus raise the rocker frame so that the roll 96 will be out of contact with the roll 97. It will be noted that the provision of the supporting frame 92 allows the feed roll 71 to be moved upwardly out of the way when the paper is being introduced into the machine, and the same is true in relation to the upper feed roll 96 which can be lifted away from 40 the lower feed roll 97 by lifting the rocker frame 117 when the paper is being introduced into the machine.

It will be understood that in both of the forms of feeding device hereinbefore described, that is, in the form illustrated in Figs. 1 to 6, inclusive, and in the other form illustrated in Figs. 7 to 14, inclusive, the feed rolls by means of which the wire, sheet material, or the like is fed intermittently, 45 might be driven without any cam and the gears could be of the same size. The object of the cam and of the gearing is to enable a long length of wire or sheet material to be fed rapidly as compared with the speed of 50 rotation of the driving shaft without em-

ploying a large and cumbersome feed roll for that purpose. The cam is so arranged as to lift the roll out of engagement with the segmental roll and then drop it into engagement with said segmental roll once in every 55 rotation of the segmental roll in the paper feeding device. By this arrangement and by proportioning the gears 101 and 102 in the relative proportion of one to two, it will be seen that by using a comparatively small 60 feeding disk or under feed roll the linear velocity of said feed roll would be as great as a roll which was twice the diameter and in which the gears 101 and 102 were made of the same size. In case the gears are used 65 one to one the cam will be unnecessary, but where the gears are made of different sizes, then the cam is used to drop one of the rolls into contact with the other and feed the material during one rotation of the driven 70 feed roll at great relative speed. The advantage obtained by this quick speed is that the feeding device is oftentimes used in connection with a machine for bending the wire or for manipulating the paper in which the 75 stock is to be fed into the machine during a certain portion of the rotation of the main shaft of said machine, and the feeding devices hereinbefore described enable the material to be fed in during, perhaps, a small 80 portion of the rotation of the shaft of the machine in which it is used, with accuracy 85 and without any danger of slipping of the same during the feeding movement.

Having thus described my invention, what 90 I claim and desire by Letters Patent to secure is:

1. A device for feeding flexible material, comprising two distinct feeding mechanisms, said mechanisms so constructed and timed 95 relatively to each other as to form a loop of said material, means to guide said material from one of said mechanisms to the other, and a brake located between said mechanisms adapted to retard the feed of 100 said material prior to its arrival at the second feed mechanism.

2. A device for feeding flexible material, comprising two distinct feeding mechanisms, said mechanisms so constructed and timed 105 relatively to each other as to provide a supply of slack material therebetween, one of said mechanisms adapted to impart a continuous feed to said material, the other adapted to impart an intermittent feed there- 110 to, and means for throwing said continuous feed out of operation.

3. A device for feeding flexible material, comprising two distinct feeding mechanisms, said mechanisms so constructed and timed 115 relatively to each other as to provide a supply of slack material therebetween, one of said mechanisms adapted to impart a continuous feed to said material, the other adapted to impart an intermittent feed there- 120 to, and means for throwing said continuous feed out of operation.

- to, and means to regulate the amount of material fed by said continuous feed mechanism.
4. A device for feeding flexible material, comprising two distinct feeding mechanisms, said mechanisms so constructed and timed relatively to each other as to provide a supply of slack material therebetween, one of said mechanisms adapted to impart a continuous feed to said material, the other adapted to impart an intermittent feed thereto, and means to regulate the length of material fed by said intermittent feed mechanism.
- 15 5. A device for feeding wire or the like, comprising two conical feed rolls having oppositely inclined peripheries, and means to guide said wire therebetween, said guiding means being adjustable longitudinally of said rolls, whereby said wire may be moved longitudinally of and between said rolls to regulate the amount of wire fed at each rotation of said rolls.
- 25 6. In a device for feeding flexible material, a rotary feed roll, a rotary segmental feed roll, and mechanism adapted to move one of said rolls toward and away from the other, whereby the length of material fed therebetween at each rotation thereof may be determined.
- 35 7. In a device for feeding flexible material, a feed roll, a segmental feed roll, gears adapted to rotate said rolls, a lever upon which one of said rolls is journaled, and a cam adapted to rock said lever and move said first-named roll toward and away from said segmental feed roll.
- 40 8. In a device for feeding flexible material, a pair of feed rolls, a lever upon which one of said rolls is journaled, means to rock said lever, and an eccentric stud upon which said lever is journaled, whereby the distance be-
- tween the peripheries of said rolls may be regulated.
9. A device for feeding wire and the like, comprising two distinct wire feeding mechanisms, said mechanisms so constructed and timed relatively to each other as to form a loop of said wire therebetween, a frame adapted to support said loop, and means to adjust said frame at different angles, whereby the free end of said wire as it is fed may be guided in a predetermined direction for the purpose specified.
10. A device for feeding wire and the like, comprising two distinct wire feeding mechanisms, said mechanisms so constructed and timed relatively to each other as to form a loop of said wire therebetween, a guide through which said wire is adapted to pass after leaving the second of said wire feeding mechanisms, a frame adapted to support said loop, and means to adjust said frame at different angles, whereby the free end of said wire as it issues from said guide may be turned to feed in a predetermined direction for the purpose specified.
11. A device for feeding flexible material, comprising mechanism adapted to impart an intermittent feed to said material, other mechanism adapted to impart a continuous feed to said material and to feed said material to said intermittent feed mechanism, and instrumentalities adapted to regulate the amount of material fed by said continuous feed mechanism.

In testimony whereof I have hereunto set my hand in presence of two subscribing witnesses.

FREDERICK L. CUMMINGS.
